UNITED STATES PATENT OFFICE.

GEORGE H. BLAXTER, OF NEW BRIGHTON, PENNSYLVANIA.

MANUFACTURE OF SEAMLESS TUBING.

No. 876,856.

Specification of Letters Patent.

Patented Jan. 14, 1908.

Application filed June 26, 1906. Serial No. 323,189.

To all whom it may concern:

Be it known that I, GEORGE H. BLAXTER, a citizen of Great Britain, residing at New Brighton, in the county of Beaver and State 5 of Pennsylvania, have invented certain new and useful Improvements in Manufacture of Seamless Tubing, of which the following is a specification, reference being had therein to the accompanying drawing.

10 My invention refers to improvements in the art of manufacturing seamless tubing, and consists in the process or method of forming an already prepared tubular blank upon a mandrel provided with a terminal ball, 15 over which the tube is forced by means of grooved reducing rolls. Also in subsequently rolling the formed tube while upon the mandrel between grooved rolls so arranged as to further compress the walls of the tube, 20 which is finally removed from the mandrel in finished shape.

The principal object of the invention is to obtain a perfectly finished smooth tube, both inside and outside.

25 The process involves the preliminary manipulation of the tubular blank to introduce it to the first set of rolls and over the terminal ball of the mandrel; means by which the mandrel and tube are transferred from 30 the first set of compressing rolls to the finishing rolls; means for centralizing and guiding the mandrel and tube-in-process; with the necessary moving or carrying elements or devices for finally removing the finished tube 35 and mandrel, as will be readily understood.

The invention has in view the forming of a smooth finished interior surface by first passing the blank over the mandrel ball to reduce the thickness of the walls and to completely remove all scale or other adhering 40 matter, and then finishing the tube on the mandrel bar under pressing rolls.

Referring now to the drawings wherein the invention is illustrated; Figure 1 represents 45 a vertical longitudinal sectional view of continuous roll mechanism for carrying out my improved process, showing the introduction of the tubular blank to the compressing rolls. Fig. 2, is a similar view showing the tube 50 surrounding the mandrel after passing through and beyond said rolls, and in progress toward the finishing rolls. Fig. 3, is a similar view showing the tube and mandrel passing through the finishing rolls. Figs. 4 55 and 5 are detail sectional views on the lines

IV. IV. and V. V. of Fig. 3 illustrating graphically the operation of the finishing rolls upon the tube.

2 represents the tubular blank a it comes from the piercing mill or other mechanism, 60 being introduced between grooved rolls 3, 3, and over the ball 4 of mandrel 5, the blank being forced between the rolls by any suitable means, as a pusher 6.

The mandrel 5 and its ball 4 are supported 65 and maintained in alinement in any suitable manner, as by under grooved rollers 7 and one or more upper rollers 8, which hold it centrally in alinement and in proper position with relation to the grooves or rolls 3. The 70 back end of mandrel 5 abuts against a gate or stop 9 which receives the force of impact of the mandrel during the process of forcing the blank 2 over the ball between the rolls, after which operation the ball ordinarily falls 75 away from the mandrel. During such operation over the ball the blank is cleared of all scale inside and out, the blank then being compressed and elongated, while carried on the body portion of the mandrel, as clearly 80 shown in Fig. 2, the walls of the tube being reduced to nearly the finished thickness desired.

Beyond the rolls 3 and arranged in suitable 85 relation to the mandrel 5 and its surrounding tube 10, are pairs of grooved rolls 11, 12, preferably located alternately in horizontal and vertical planes as shown, whereby the first pair of rolls will engage the tube 10 at opposite sides, the next succeeding pair engaging 90 it at intervening positions, at the same time. It will be understood that any number of pairs of rolls may be employed or that their position with relation to each other may be varied within the judgment of the operator 95 or depending upon the work in hand. The operation and effect of such grooved rolls 11, 12, is to further compress the walls of the tube 10 upon mandrel 5, giving the required uniform thickness throughout, and effecting 100 a smooth polished surface both inside and out. The further result of the operation of said rolls is that the internal diameter of the tube 10 is slightly increased and the tube is freed from adherence to the mandrel 5, by 105 reason of the fact that the compressing faces of the rolls operating at opposite sides, tend to cause the tube to bulge out at the intervening portions as indicated at 13 Figs. 4 and 5, thus greatly facilitating the work of re- 110

2
moval of the tube from the mandrel bar. After passing through said rolls 11, 12, the tube is removed from the mandrel bar by any suitable means as hydraulic pushing mechanism or otherwise, and will be found to have a highly polished finish both inside and out and of the uniform desired thickness and diameter. The internal finishing is primarily due to the action of ball 4 which removes 10 any adhering scale or dirt, and thus allows the finishing passes to be made on the clean metal of the mandrel bar, contacting with the clean interior of the blank.

Changes or variations may be made in the 15 mechanism by which the operation is performed, or in the steps of the process, but all

such changes are to be considered as within the scope of the following claims.

What I claim is:

In the manufacture of seamless tubing, the 20 process of forcing a heated tubular blank, between reducing means over and onto a mandrel bar, and then reducing the tube surrounding the mandrel bar between said bar and outside reducing means.

25 In testimony whereof I affix my signature in presence of two witnesses.

GEORGE H. BLAXTER.
